Primary Examiner — Susan Moon Lee(74) *Attorney, Agent, or Firm* — Additon, Higgins & Pendleton, P.A.**(57) CLAIM**

The ornamental design for an indicia scanner, as shown and described.

DESCRIPTION

FIG. 1 is a perspective view of an indicia scanner;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof;

FIG. 8 is another perspective view thereof;

FIG. 9 is another perspective view thereof; and,

FIG. 10 is another perspective view thereof.
